UNITED STATES PATENT OFFICE.

HEINRICH WALDES, OF WRSCHOWITZ, NEAR PRAGUE, AUSTRIA-HUNGARY.

SPRING DEVICE FOR SPRING-PRESSED BUTTONS.

1,084,377.

Specification of Letters Patent.

Patented Jan. 13, 1914.

Application filed April 23, 1913. Serial No. 763,017.

To all whom it may concern:

Be it known that I, HEINRICH WALDES, a citizen of the Austro-Hungarian Empire, and residing at Wrschowitz, near Prague, 5 Bohemia, Austro-Hungarian Empire, have invented a certain new and useful Improved Spring Device for Spring-Pressed Buttons, of which the following is a description.

This invention relates to separable fasteners comprising spring pressed buttons.

In a common form of stud, hood and spring device the spring is usually located in the upper part of the hood member of the fastener and passes through slots in the 15 hood into recesses in the neck of the button of the stud member and holds the parts together when the fastener is closed. Hitherto the hood has been provided with diametrically opposite straight slots, in which 20 straight shanks of the two ends of the spring were situated, which engaged recesses in the neck of the button when the parts were closed.

The object of the present invention is to 25 provide means by which the engaging parts of the spring are enabled to penetrate deeper recesses in the neck of the button.

Figure 1 of the accompanying drawings represents a vertical diametrical section on line 1—1 of Fig. 2 of a separable fastener showing one form of this invention. Fig. 2 represents a horizontal section thereof. Fig. 3 represents a horizontal section of the button head, showing the locking slot there- 30 of constituting a part of this improvement indicated by the curved lines f^3 and the old form of such slots by the straight dotted lines e .

The same reference letters indicate corresponding parts in the different figures.

In the form of this invention herein illustrated the spring member comprises the usual approximately semi-circular connecting shank f disposed at the outer rim of the 45 attaching plate c of the hood member and has at its opposite ends two springs integral therewith opposite each other at opposite sides of the hood c' of said hood member c .

Each of these springs is in the form of a double loop, the sides f^1 and f^2 of which are 50 arc-shaped and concentric or approximately so. The side f^2 is in the form of an elongated bend which projects through the slot d' in the side of the hood c' and engages the arc-shaped recess b^2 in the sides of the stud 55 b' of the stud or button member. The stud b' of the stud member is provided on its opposite sides with recesses b^2 which curve inwardly and afford wide bearings for the engagement of the spring. The slots d' of 60 the hood c' are curved at their ends to correspond with the curvature of the recesses b^2 of the stud. By means of this arrangement the engagement of the springs f^2 , projecting through the slots d' of the hood c' and entering into the recesses b^2 in the stud b' , is 65 very considerably increased without enlarging said slots or weakening the hood. This arc-shaped projecting form of the springs is embodied in a spring member of this character preferably by means of the double loop having arc-shaped sides. 70

In Fig. 3 the curved lines f^3 indicate the depths of the locking recesses in the button head and the dotted straight lines e indicate 75 the old form of such recesses, these lines indicating the relative depths of the new locking recesses and the shallowness of the old construction.

I claim as my invention:

1. A separable fastener comprising a stud member including an attaching plate and a stud thereon provided with concave recesses on opposite sides, a socket member including an attaching plate and a hood provided on 85 its opposite sides with slots adapted to register with said recesses, and arc-shaped springs on opposite sides of said hood member adapted to engage said arc-shaped recesses of the button members. 90

2. A separable fastener comprising a stud member including an attaching plate and a stud thereon provided with concave recesses on opposite sides, a socket member including an attaching plate and a hood provided on 95 its opposite sides with slots adapted to reg-

ister with said recesses, and a spring member including an arc-shaped connecting shank disposed on the attaching plate of the hood member and having at its opposite ends on opposite sides of said plate springs integral with said connecting shank, each spring being in the form of a double loop, the sides of which are arc-shaped and con-

centric, their inner sides engaging said concave slots and recesses. 10

In testimony whereof I affix my signature in the presence of two witnesses.

HEINRICH WALDES.
